(57) **CLAIM**

The ornamental design for a putter head, as shown and described.

DESCRIPTION

FIG. 1 is a front elevational view of the putter head;

FIG. 2 is a rear elevational view of the putter head of FIG. 1.

FIG. 3 is a left elevational view of the putter head of FIG. 1.

FIG. 4 is a right elevational view of the putter head of FIG. 1.

FIG. 5 is a top plan view of the putter head of FIG. 1.

FIG. 6 is a bottom plan view of the putter head of FIG. 1; and,

FIG. 7 is a front elevational view of a second embodiment of the putter head as disclosed in FIG. 1, the undisclosed the top, bottom, rear, left and right sides are identical to that disclosed in the first embodiment.
